BREECH AND FIRING MECHANISM FOR
RECOILLESS FIREARMSWilliam J. Kroeger and Clarence Walton Musser,
Philadelphia, Pa.

Application February 2, 1949, Serial No. 74,164

3 Claims. (Cl. 89—1.7)

(Granted under the act of March 3, 1883, as
amended April 30, 1928; 370 O. G. 757)

1

The invention described herein may be manufactured and used by or for the Government for governmental purposes without the payment of any royalty thereon.

The present application is a continuation-in-part of Application Serial No. 577,830 filed on February 14, 1945 now Patent Number 2,472,111 in the names of William J. Kroeger and C. Walton Musser for "Recoilless Firearm and Ammunition Therefor."

Our invention relates to firearms of the recoilless type, and it has special reference to non-recoil guns wherein the forces of rearward reaction that result from projectile discharge are neutralized by forwardly acting counterforces simultaneously set up by the propellant charge's combustion.

Broadly stated, the object of our invention is to improve the design and extend the usefulness of recoilless guns wherein the named recoil neutralization is effected by a rearward escape of generated powder gas through openings or orifices in the gun's breech.

A more specific object is to provide improved chamber and breech constructions for such recoilless guns.

A further object is to increase the simplicity, ruggedness and compactness of breech actions and of firing mechanisms for recoilless firearm use.

An additional object is to provide improved means for loading and firing the gun.

Other objects and advantages will become apparent as the disclosure and description hereof proceed.

In the aforementioned parent application we disclosed a number of factors to be necessary for a satisfactory operation of our inventive recoilless firearm. In constructing one recoilless firearm pursuant to that disclosure we: (a) make the gun's chamber of substantially larger diameter than the ammunition cartridge case which fits therein; (b) support this cartridge case centrally in the enlarged chamber solely from the two ends of the case; (c) provide in the gun's breech a rearwardly opening orifice of unique annular nozzle design, that is capable of ready adjustment for optimum area; (d) use a cartridge case having a metal wall which is perforated throughout the length and circumference of the case and which permits discharge of propellant combustion gases radially against the chamber's surrounding wall and thence rearwardly from the gun out through the annular orifice of the gun's breech; (e) pre-engrave the projectile for ready passage through the rifled bore of the gun's barrel; and

2

(f) so coordinate the breech and firing mechanisms as to permit quick and convenient loading and firing.

The invention to which the present specification is essentially restricted is the specific breech closure structure and firing mechanism used in the gun first disclosed by the aforementioned parent application. The present invention itself, together with illustrative embodiments thereof will best be understood from the following description taken in conjunction with the accompanying drawings wherein:

Fig. 1 is a rear view of a recoilless gun of 75 mm. caliber which incorporates our inventive features, and is shown with the breech bar thereof horizontal and the breech block secured within the chamber where it constitutes the inner wall of an annular orifice;

Fig. 2 is a similar view to that of Fig. 1 except that the breech bar and breech block are shown after having been rotated to the unlatched position;

Fig. 3 is a rear perspective view of the gun with its breech block withdrawn from the chamber and swung downwardly on a supporting hinge;

Figs. 4—5 are enlarged showings of "open" and "closed" breech locks with which the weapon is provided;

Fig. 6 shows in detail the breech block supporting hinge;

Fig. 7 shows the hinge of Fig. 6 in front side perspective and with its hammer rollers in place;

Fig. 8 is a section on line 8—8 of Fig. 1 showing further details of the breech block, locking devices therefor, the firing mechanism, and trigger linkage;

Fig. 9 is a section on line 10—10 of Fig. 1 through hinge and breech bar rollers by which the firing mechanism's hammer is cocked upon each unlatching of the breech;

Fig. 10 is an enlarged section on line 10—10 of Fig. 8 through the gun's trigger handle with the trigger and associated safety mechanism in place therein;

Fig. 11 is an enlarged section on line 11—11 of Fig. 8 similar to Fig. 10 but taken from a different level of the trigger handle;

Fig. 12 is a view taken from line 12—12 of Fig. 8 to show from another vantage point the relationships of the trigger, the trigger key and the safety button;

Fig. 13 is a section on line 13—13 of Fig. 3 showing details of the breech block and trigger handle when in the open breech position;

Figs. 14—15—16—17—18 are views illustrative of

how cocking of the hammer is effected by each unlatching rotation of the breech bar; and

Fig. 19 is an enlarged reproduction of the hammer and cocking roller mechanism first illustrated by Fig. 9.

The complete recoilless gun

Our inventive improvements are here illustratively disclosed as being incorporated in a military weapon of 75 mm. caliber capable of a completely recoilless firing of projectiles. As the description proceeds, it will become apparent that our improvements may also be applied to firearms of characters, sizes, and shapes other than the one here disclosed and that the represented 75 mm. open breech weapon thus has been chosen only to illustrate and not to limit the inherently wide application and scope by which these improvements are characterized.

The illustrative recoilless firearm here shown consists of a barrel 30; an enlarged chamber 31 secured to the rear of this barrel and having the uniquely tapered shape represented; a breech block 33 partially closing (see Figs. 1-2) the rear of the chamber; a breech bar 34 secured to the block and carrying trigger and breech handles 35-36; a pair of carrying handles 37-38 (see Fig. 3); and a sight (not shown) for aiming the gun in conventional manner.

As here represented the carrying handles 37-38 are suitably clamped to the barrel 30 as shown in Fig. 3. These handles, in conjunction with the trigger and breech handles 35-36 enable two or four men readily to carry the weapon from one location to another.

Ammunition having a novel "perforated cartridge case" (only the rear or base end of the case is shown at 40 in Fig. 8, the perforations in the wall of the case being further along the sidewalls thereof and are not shown in the drawings) is loaded into the weapon from the breech thereof in a manner presently to be explained. Such loading may be done either by the man who fires the weapon or by an assistant.

The chamber and breech

As here shown, the gun's chamber 31 takes the form of an enlarged cylinder uniquely tapered at its forward end and there affixed to the rear of barrel 30 in any integrally secure manner as by the aid of screw threads (not shown). In Fig. 3 this juncture of the barrel and chamber is represented by the flange 45 which encircles the forward end of the tapered chamber. The innermost side of this flange (not shown) bears the threads which are used to secure barrel 30 thereto.

As the drawings also show, the gun's breech block is a "spider-like" element removably secured within the rear end of chamber 31 and constitutes only a partial closure therefor. It takes the form of a cylindrical block 33 which is radially spaced from the chamber wall in a manner to form a substantially annular orifice that leads from the chamber's interior to the rear exterior of the gun. As reference to Figs. 1-2-3 and 9 will show, the breech block tapers inwardly from front to rear.

Four locking lugs shown at 49 extend radially from this central breech block 33 and interfit with mating protrusions 50 on the chamber wall interior. Each locking lug 49 carries threads on the periphery thereof whose continuity is interrupted, as shown in Fig. 3, and each mating protrusion 50 is provided with similar interrupted threads indicated at 51. When these two sets of

threads are engaged, as in Figs. 1 and 8, they securely lock the breech block 33 within the rear of the chamber 31.

The chamber wall spaces which circumferentially separate the locking protrusions 50 have a diameter larger than the maximum for the breech lugs 49 and this relationship enables free longitudinal movement by these lugs through the spaces named. This movement is utilized in inserting the breech block within the chamber and also in withdrawing the block therefrom, all in a manner presently to be described.

When inserted and locked within the chamber 31, as shown in Figs. 1 and 8, this breech block 33 constitutes a firm support for the ammunition which it helps to position within the weapon. The steel of its central core structure is of sufficient thickness and strength to stand, with a factor of safety of well over two, the maximum rearward thrust exerted thereon during firing.

Cooperating with the gun's barrel and the just described chamber and breech structure is ammunition having the earlier mentioned unique perforated case (only the rear end of which is shown at 40 in Fig. 8). As explained in greater detail in the aforementioned parent application, the purpose of the perforations (not here shown) in cartridge case 40 is to permit the powder gases to issue therefrom in a radial manner, so as to expand within the enlarged chamber 31 and become exhausted through the annular orifice 48 to the rear exterior of the gun with a torque equal but opposite in direction to that caused by a projectile (not shown) upon being fired through the gun's barrel.

In the loaded position represented by Fig. 8 the cartridge case head 63 is accordingly engaged by a mating recess 139 in the front of the breech block. This recess 139 flares outwardly toward the front so as more conveniently to receive the case head during loading. By its engagement with the head, the rear of cartridge case 40 is centrally positioned within chamber 31 and the entire case is restrained against backward movement. Thus positioned, the primer (which is carried within the primer percussion element 56 shown in Fig. 8) carried by the cartridge case head 63 is engageable by a firing pin 66 protruding through the center of the breech block 33 and there actuated by firing mechanism later to be described.

When the primer is so engaged a booster powder charge 58 contained in booster tube 57 is ignited and the flame therefrom spreads through openings 59 in the wall of tube 57 and thereby ignites the propellant charge 55. Ignition of the propellant charge causes the expulsion of the ammunition round's projectile (not shown) from the gun.

60 *The annular orifice and recoil neutralization*

The 75 mm. recoilless firearm illustratively here shown effects recoil neutralization in the unique manner taught by our earlier mentioned co-pending application Serial No. 577,830; that is, the forces of rearward reaction are neutralized by forwardly acting counterforces. These counterforces are produced by acceleration of the rearwardly escaping generated powder gases with an accompanying pressure gradient within the chamber and venturi. Therefore, the pressure forces rearwardly acting against the obstruction presented by the breech can be counteracted by the forwardly acting pressure forces acting on the small annular forward portion of the chamber

31, the forwardly acting drag forces of the projectile (not shown) in the rifled barrel 30, and by the forwardly acting force components produced by the pressure of expanding gases in the conical and divergent portions of the earlier indicated annular orifice 43 between the gun's breech block 33 and the rear wall of chamber 31 wherein this block is secured.

As the drawings clearly show, this annular orifice extends all the way around that block's central core and is obstructed only by the four radial lugs 49 which engage with the four mating protrusions 50 of chamber 31. All circumferential space between these lugs thus constitutes the named annular orifice 48 which leads from the interior of chamber 31 rearwardly to the exterior of the gun.

Upon ignition of the propellant powder 55 and the resultant discharge of the projectile (not shown) forwardly out of barrel 30 there is expelled through the perforations (not shown) of cartridge case 40 combustion gases which are projected radially against the surrounding chamber wall and then rearwardly out of the chamber through the annular orifice now being described. By thus acquiring momentum opposite to that of the forwardly moving projectile (not shown) the explosive gas thus expelled sets up the aforesaid counterforces which tend to neutralize recoil.

In our improved 75 mm. weapon here shown we supplement this momentum effect by making the gun's annular breech orifice 48 of the represented "nozzle" or "cone" shape indicated best by Fig. 9. Starting with a relatively narrow radial width at its front or throat, the annular orifice flares inwardly toward the rear with an angle spread of approximately 20°. Such an angle yields a satisfactory forward force component due to an expansion of the powder gases in passing rearwardly through the orifice as earlier explained.

For maximum effectiveness it would be desirable to extend the annular or nozzle orifice to a substantial axial dimension, but practical considerations show that acceptable performance is achieved when the nozzle orifice has the relatively short length which the drawings indicate. (See Fig. 9 in particular.) Thus, we prefer to select for the nozzle an axial length which gives a rear or discharge area of approximately two and one-half times the area of the orifice's front or throat area. Dimensions other than that shown may of course be utilized with varying degrees of relative effectiveness.

In our achievement of complete neutralization of recoil we find that there exists an optimum ratio between the bore area of the gun's barrel and the throat area of the breech orifice. The factors which determine the value of this optimum ratio are more completely appraised by our earlier mentioned co-pending application Serial No. 577,830 and other cases to which reference has therein been made. As those cases show, the required bore-to-throat area ratio is dependent primarily upon the amount of expansion obtained in the nozzle 48 and to a lesser extent upon such factors as the relative weights of the powder and projectile. In a firearm of the annular orifice type here disclosed this ratio for zero recoil is found to lie within a range from about 1.40 to about 1.60.

Our improved weapon includes provision for adjusting this ratio to the optimum value which during actual firing does in fact produce zero recoil. In the illustrative arrangement disclosed, this provision takes the form of a breech orifice cone 54, secured in the position illustrated in

Fig. 8 by four screws 71 (also see Fig. 3), which also serves in conjunction with breech block 33 to support the rear of cartridge case 40. It will be noted that cone 54 determines the weapon's ratio of bore area-to-throat area as a result of its defining the forward interior wall of the weapon's annular orifice shown at 48 in Fig. 9. As that figure further indicates, the rear interior wall is defined by the breech block 33 when same is secured within the chamber.

While occupying such a portion of the total orifice area as is needed to provide the necessary adjustment, this cone 54 does not alter the basic nozzle shape thereof and hence it constitutes a particularly efficient means for effecting the required adjustment. The maximum throat area is of course realized when the outside diameter and axial length of cone 54 are relatively small; hence the smallest side of the adjusting cone is selected to afford a throat area large enough to meet the maximum requirements.

Applying the figures earlier stated, use of such a minimum diameter cone might give a bore-area to throat-area ratio of the 1.40 lower limit. To change this ratio to the other extreme of the named 1.60 maximum, it is merely necessary to install an adjusting cone 54 of sufficiently larger diameter and axial length as to cut down the total throat area by the requisite amount; and to obtain ratios of intermediate values, there may be substituted adjusting cones 54 of varying intermediate sizes.

Choice of the exact preferred cone size is most effectively determined by trial firing in a pendulum or other gun suspension which is free to swing and thereby indicate the presence, direction and magnitude of recoil should same exist. In the illustrative 75 mm. weapon represented, zero recoil is found to call for an adjusting cone which gives a bore-area to throat-area ratio of the order of 1.48. With such adjustment the nozzle throat has a total area which is approximately one-tenth of the cartridge case's total area of perforations (not shown).

45 *Neutralization of rotational reaction*

As pointed out by our co-pending application Serial No. 577,830, firearms with rifled barrels experience a rotational reaction by virtue of the spinning motion that firing imparts to the projectile (not shown). Depending on the direction of the barrel's rifling, the projectile (not shown) will be given a clockwise or counterclockwise rotation. Whatever the direction of this rotation, the result thereof will be an imparting by the projectile of a torque in the opposite direction but of equal magnitude to that received by the barrel.

Our improved 75 mm. weapon here shown includes provision for neutralizing such reactive torque by causing the explosive gases which rearwardly discharge through the annular breech orifice 48 to impart to the weapon counterbalancing torque of the same magnitude as that which the rifled barrel imparts to the projectile. This provision is effected by so specially shaping the chamber protrusions 50 and breech block locking lugs 49 that the gases passing through orifice 48 have angular momentum imparted thereto.

Each of these lugs 49 and chamber protrusions 50 has sidewalls that are slightly out of parallel with the gun's axis. This side wall arrangement is such that the powder gases flowing rearwardly through the orifice 48 are made to rotate about the gun's axis. By reason of this counter-acting spin thus given to the gases, there is imparted to the chamber 31 a torque counteracting

that applied by the projectile (not shown). Only the relatively small degree of angular twist shown is found sufficient to make the thus imparted torque of the same magnitude as the barrel 30 imparts to the projectile (not shown) in advancing it through the rifled bore.

All neutralizing torque thus set up by the escaping gases is exerted on the sides of the locking surfaces in the venturi 48 and through chamber 31 is transmitted to barrel 30, and in this way the forces of rotational reaction are neutralized in a very simple yet highly effective manner.

The chamber protrusions 50 and locking lugs 49 in the drawings are shaped so as to function as described above in offsetting the effect of barrel riflings (not shown) that have a right-hand twist. However, if the gun barrel were to be rifled with a left-hand twist, rotational reaction could be neutralized in exactly the same way merely by shaping the chamber protrusions 50 and locking lugs 49 in the opposite sense.

Breech block's withdrawal from chamber

Explanation has already been given of how the breech block 33 is secured in the rear of chamber 31 by the aid of that block's locking lugs 49 and the mating protrusions 50 on the chamber interior. In the "engaged" position represented by Figs. 1, 8 and 9 this support is all that is needed to hold the breech block in place, and it is fully adequate to restrain the maximum chamber pressures which combustion of the propellant charge 55 sets up.

To facilitate loading and removal of the cartridge case 40 after firing, provision is made for releasing this breech block 33 from its chamber attachment, rearwardly withdrawing it from the chamber 31 and swinging it out of alignment with the chamber interior to the downward position shown by Figs. 3 and 13. The earlier mentioned breech bar 34 to which the forwardly extending handles 35-36 are affixed comes into play during these actions.

Then also utilized is a hinge support fixture 75 having its upper end connected with breech block 33's center and its lower end connected through a hinge pin 80 and an attachment block 76 (see Figs. 3 and 13) to chamber 31's lower sidewall. Through these elements the breech block 33 continues to receive support from the gun after it has been withdrawn from the chamber.

The earlier mentioned breech bar 34 is secured to the breech block 33 by means of four bolts shown at 77 in Figs. 1-2. Intermediate this bar and the main body of the block is an offset ring-like extension 78 of the hinge fixture 75. Around this ring extension both the breech block 33 and the bar 34 may be turned between the "horizontal bar" position of Fig. 1 and the "inclined bar" position of Figs. 2-3. In the gun here shown the range of this angular movement is of the order of 45 degrees, as contrast of Figs. 1 and 2 will indicate.

Clockwise rotation of the weapon's breech bar 34 serves to engage the breech locking lugs 49 with the mating threads of chamber protrusions 50 and thereby secures the breech block 33 within the chamber 31 as earlier explained; clockwise rotation moves the locking lugs out of engagement with the chamber protrusions, and into the circumferential region between protrusions. In the latter position, the breech block 33 is freed for rearward withdrawal from the chamber.

Appropriate limits of such angular travel are

established by those portions of the hinge support 75 which respectfully engage the lower sides of breech bar 34 as shown in Figs. 1 and 2. The former figure shows the bar and breech block 33 at the limit of counterclockwise rotation wherein the breech block is securely locked in this chamber 31; the latter figure shows the bar and block at the clockwise limit of rotational travel in which the block has been freed for withdrawal from the chamber.

Serving to support the breech block upon such withdrawal is the earlier mentioned hinge fixture 75 secured at its lower end to chamber wall 31 as already described. Once disengaged from chamber 31 as shown in Fig. 2, the breech block 33 plus bar 34 and handles 35-36 are free for rearward withdrawal and downward swinging around hinge pin 80 to the position represented by Figs. 3 and 13.

When the breech block 33 is withdrawn from chamber 31, the entire interior area of that chamber is unobstructed in a way permitting ready insertion of a projectile (not shown) and cartridge case 40 into the gun or ready withdrawal of a fired cartridge case from the weapon.

To reinsert the breech block into the chamber, it is merely necessary to swing the block upwardly from the position shown in Figs. 3 and 13; move it forwardly into the chamber's open end as indicated by Fig. 2; and finally give handles 35-36 and bar 34 a turning movement which brings the block to its counterclockwise limit of rotation in which the locking lugs 49 thereof engage the chamber's mating protrusions 50 as shown in Figs. 1 and 8.

The "open" breech lock

Our improved weapon here illustrated utilizes two locking devices by which the breech block 33 is respectively secured in the "inclined bar" position of Figs. 2 and 3 and in the horizontal position of Fig. 1. The first of these devices will be spoken of as the "open" breech lock and the second as the "closed" breech lock.

The purpose of the "open" breech lock is to keep the breech block 33 and its attached bar 34 in the inclined position of Figs. 2-3 at all times except when the block is fully inserted into the gun's chamber 31. This lock thus serves to hold the bar 34 and the breech block 33 in the inclined position of Figs. 2-3 as long as the breech block remains withdrawn from the chamber, as in Figs. 3 and 13.

The mechanism utilized includes a locking bar 82 having the general shape which Figs. 4 and 13 show; a slot 83 cut into the forward face of hinge fixture 75 as shown in Figs. 6, 7 and 13 for accommodating bar 82 as shown in Fig. 13; a slot 84 cut into the rear face of breech block 33 as shown by Figs. 1 and 13 for at times receiving a portion of bar 82 as shown in Fig. 13; and a leaf spring 85 beneath the bar in hinge slot 83 as shown in Fig. 13 which urges that bar toward the breech block.

As long as the breech block 33 is fully inserted into the chamber 31, the bar 82 is held completely within the hinge slot 83 by contact of the forward face of the bar with the rear face of the chamber's lower protusion 50. Under this condition the bar 82 is completely withdrawn from engagement with the breech block slot 84 and no rotative restraint is imparted thereby to the breech block. Insofar as bar 82 is concerned, the breech block 33 may now be rotated throughout its complete range of travel.

Once, however, the breech block 33 is withdrawn from chamber 31, leaf spring 85 then pushes bar 82 into the breech block slot 84 as soon as that slot is brought into alignment with the bar. From Figs. 1-2-3 it will be seen that such alignment is effected when the breech block is rotated to the fully unlatched position which Fig. 2 shows. In that position the bar moves forwardly into the breech block slot as indicated by Fig. 13.

Such movement locks the breech block 33 against potential movement with respect to hinge mounting 75, in the forward slot 83 of which the bar 82 is carried. Such locking action continues as long as the breech is withdrawn from the chamber. It prevents, for example, the handles 35-36 and the breech bar 34 from being moved out of the inclined position which Figs. 2-3 represents. Such prevention is made especially desirable by certain operating characteristics of a unique firing mechanism later to be described.

Upon reinsertion of breech block 33 into the chamber 31, locking bar 82 is once again pressed completely into its hinge slot 83 as indicated in Fig. 2 by contact of its forward face with the rearward face of the chamber's lower protusion 50. This breaks the lock between breech block 33 and hinge mounting 75 and allows the block to be turned by handles 35-36 and bar 34 from the disengaged position of Fig. 2 to the chamber-engaged position of Fig. 1.

The "closed" breech block

The "closed" breech block earlier mentioned now becomes effective to hold the breech block 33 in this horizontal bar position of Fig. 1 until after the weapon's firing pin 66 moves forward. The mechanism utilized includes a "closed" locking pin and bar combination 88-89 as shown in Figs. 5 and 8 and assembled with the breech block 33 and breech bar 34 as shown by Fig. 8; a slot 90 cut into the right side of hinge ring 79 as shown in Figs. 6 and 8 to be engaged by locking bar 89 as indicated by Fig. 8; a spring 91 which urges the rear of bar 89 into hinge slot 90 as indicated by Fig. 8; and a firing mechanism hammer 92 having on its side wall a groove 106 whose bottom is tapered so as conveniently to engage an end of bar 89 in the manner also shown by Fig. 8.

This hammer 92 is carried within a hollow case 93 which is integral with and extends back from the breech bar 34 in a manner indicated by Figs. 8, 9, 13 and 19. As will later be explained, this hammer is moved rearwardly to the "cocked" position shown by Figs. 8 and 13 upon each unlatching rotation of breech bar 34; and it is released for forward advancement to the "fired" position shown by Figs. 9 and 19 upon each depression of the gun's trigger 94 in handle 35.

As long as hammer 92 is cocked, the taper of groove 106 in the side wall thereof (indicated by Fig. 8) allows spring 91 to force locking bar 89 inwardly into engagement with hinge ring slot 90 (Fig. 8) and thereby restrain the breech block and its bar 34 from rotative movement with respect to the hinge. This assures that the breech bar must remain in its chamber-engaged position of Figs. 1 and 8 unless either the hammer 92 moves forwardly to the position of Figs. 6, 9 and 19 or unless locking pin 88 (Figs. 1, 2 and 8) is manually moved to the right against spring 91 (see Fig. 8).

Upon release of hammer 92 to its forward or fired position of Figs. 9, 17 and 19 the slow taper of groove 106 in that hammer's side wall wedges bar 89 outwardly against spring 91 and thereby

moves that locking bar out of the hinge ring's slot 90. (See Fig. 6.) This wedging action imposes such small restraint upon forward movement of the hammer that it in no way interferes with the desired operation of our weapon's firing mechanism.

Each firing of the weapon therefore automatically unlatches the breech block's "closed" locking bar 89 and frees the breech block 33 for clockwise rotation and subsequent withdrawal from chamber 31. This result occurs whether ammunition is or is not present in the weapon.

A similar release of the "closed" breech lock may be effected manually as earlier mentioned. Such manual actuation requires only that the locking pin shown at 88 in Figs. 1, 2 and 8 be pushed to the right against spring 91 (see Fig. 8). Such pushing releases the breech block for clockwise rotation and withdrawal out of the chamber even though the weapon's hammer 92 may be cocked as indicated by Figs. 8, 13 and 18.

The firing mechanism

For igniting the ammunition's propellant charge 55 at the will of an operator use may be made of any suitable firing mechanism. Here represented by way of illustration is a unique mechanical type of firing mechanism by the aid of which an operator may fire the weapon by a simple depressing of the earlier mentioned trigger 94 carried by handle 35.

In the disclosed arrangement the firing pin 66 carried by the gun's breech block 33 receives through direct attachment with the earlier mentioned hammer 92 a firing blow created by the forward movement of that hammer. The force incident to that forward movement originates in a spring 97 carried between the hammer 92 and case 93 as most clearly shown in Figs. 8, 9, 13 and 19. This force is made available for firing the gun when a sear shown at 98 in Fig. 8 is withdrawn from in front of the hammer.

The illustrated hammer 92 takes the form of a metal cylinder having the general appearance best indicated by Figs. 13 and 18 inclusive. The firing pin 66 is screwed into the front of this cylinder and thus at all times moves in unison therewith. This movement is between the "cocked" position of Figs. 8, 13 and 19 and the "fired" position of Figs. 9, 17 and 19.

Cocking of the hammer

As earlier stated, cocking of the hammer from the forward position of Figs. 9, 17 and 19 to the rearward position of the earlier named figures is effected by rotation of the breech block 33 and its bar 34 from the "horizontal bar" of Fig. 1 to the "inclined bar" position of Fig. 2. Such rotation is translated into rearward movement of the hammer by means of two pairs of rollers shown at 100 and at 101 in Figs. 14 to 19, inclusive.

Rollers 100 are carried by the hinge ring 79 (see Figs. 7 and 19), while rollers 101 are carried by the breech bar 34. Both sets of the named rollers engage with longitudinal slots 103 in the outer surface of hammer 92. The forward portion of each of these slots is tapered as shown at 104 in Figs. 13, 14, 17, 18 and 19.

With the breech bar 34 in the horizontal position of Fig. 1 both sets of these rollers 100-101 lie along line 9-9 of Fig. 1, and sections therethrough appear as shown in Figs. 9 and 15. The hammer 92 is shown by Figs. 9 and 17 in its forward or fired position wherein firing pin 66 has

by the hammer and spring 97 been moved to its forward limit of travel.

Upon rotation of the breech bar 34 from the horizontal position of Fig. 1 to the "inclined bar" position of Fig. 2 the forward or hinge rollers 100 remain stationary, while the rearward or bar rollers 101 rotate the hammer clockwise as viewed from the rear, from the position shown in Fig. 15, to that indicated by Fig. 16. Fig. 15 will be seen to correspond to Fig. 14, except that the latter shows the hammer and its rollers as viewed from the front end of the gun in Fig. 8, while the former shows the same part as viewed from the rear or breach end of the gun. Fig. 16 is similar to Figs. 14 and 15, except that in Fig. 16 the hammer and its rollers are shown in the position they assume when the breech bar 34 is turned to the inclined position of Fig. 2, whereas in Figs. 14-15 the hammer and its rollers are shown in the position they assume when the breech bar 34 is in the horizontal position of Figs. 1 and 8.

The named rotative movement brings the tapered sides 104 of the hammer slots 103 against stationary rollers 100, and by a camming action best apparent from Figs. 17-18 forces the hammer 92 backwards against spring 97 and into the cocked position shown by Figs. 8 and 13. When the cocked position has been reached the sear shown at 98 in Fig. 8 is by spring action later to be described forced inwardly ahead of the rear face of a restraining slot shown at 140 in Figs. 8-9.

Release of the hammer

In this position the sear 98 holds the hammer cocked until such time as trigger 94 may be depressed. Upon such depression of the trigger the sear is withdrawn from its engagement with the restraining slot 140, and hammer 92 plus firing pin 66 are allowed to move forward due to the expansive force of spring 97. This forward movement brings firing pin 66 against the ammunition's primer 56 and thereby fires the weapon.

The named forward movement can, of course, take place only after the breech bar 34 has been returned to the horizontal position of Fig. 1. In that horizontal position bar rollers 101 are again realigned with hinge rollers 100 as shown in Fig. 15. This realignment frees the hammer for unrestrained forward movement as soon as sear 98 is withdrawn from the latching slot 140 therein.

In the illustrative construction shown hammer 92 is fitted relatively close to the inner walls of hammer housing 93. In order that "air pumping" action resulting from the closeness of this fit will not restrain longitudinal movement of the hammer with respect to the casing, there is provided in the hammer's sides a second pair of longitudinal slots indicated in 107 in Figs. 8, 14, 15 and 16. These slots allow free passage of air into the space behind the hammer upon forward or firing movement thereof, and from that rearward space upon backward or cocking movement thereof.

Complete hammer operation

The just described hammer mechanism will thus be seen to operate as follows. Following each firing of the weapon, the firing pin 66 and hammer 92 occupy their forward positions as shown by Figs. 9 and 19 while the breech block 33 is still locked in chamber 31 with the bar 34 horizontal as shown in Fig. 1.

Rotation of the breech bar 34 to the inclined position shown in Fig. 2 causes the bar rollers 101

to rotate the hammer 92 clockwise as viewed from the rear, and this action in turn causes hinge rollers 100 to cam the hammer 92 backwardly against spring 97 as already explained by reference to Figs. 8, 13 and 18. The so-cocked hammer now occupies the position shown by Figs. 8 and 13. Retention in that position is effected by sear 98 blocking forward movement of the hammer as shown in Fig. 8.

10 This blocking continues during subsequent withdrawal of the breech block 33 from the chamber to the position shown by Figs. 3 and 13. It also remains effective during reinsertion of the breech block into the chamber and engagement therewith by restoration of breech bar 34 to the horizontal position of Fig. 1. Such restoration re-aligns rollers 100-101 from the condition shown by Fig. 18 to that indicated by Fig. 14.

15 This realignment conditions the hammer for subsequent forward movement upon withdrawal of the restraining sear 98. Upon such withdrawal spring 97 forces the hammer and its firing pin 66 rapidly forward into contact with the cartridge case's primer 56 and thereby detonates the 20 primer and fires the weapon. By this action the firing mechanism is returned to the original "after firing" condition with which this description started.

The trigger mechanism

25 Cooperating with the hammer 92 and its just described cocking mechanism is a trigger mechanism which will now be explained. This mechanism utilizes the earlier mentioned sear shown at 98 in Fig. 8; the earlier mentioned trigger shown at 94 in the same figure as protruding from the forward end of trigger handle 35; and a rotatable safety button 109 carried in the hollow end of that handle as also shown by Fig. 8.

30 The sear 98 takes the form of a round rod slidably housed in the left half of breech bar 34 between the rear wall of that bar and a front cover plate 108 and having an outer end which is inclined as shown by Fig. 8 into a mating opening in the inner end of the plunger-like trigger 94. This trigger is axially movable within handle 35 and safety fixture 109, but is by a key 111 prevented from rotation with respect thereto. By a "double" action of a trigger spring 110 this trigger 94, when not compressed into firing position 35 is urged toward its outward limit of travel. This travel limit normally would be the safety button's opposed lower or inner projections 114; however, the intervening agency of the spring 55 110, being connected to the safety button below the projections 114 and also connected to the trigger 94, limits such travel to the distance over which spring 110 may be compressed against projections 114. Such urging holds sear 98 against hammer 92 as shown in Fig. 8.

60 Reference to Fig. 8 shows that spring 110 not only exerts tension between parts 94 and 109 but that it is also arranged to impart turning effort on safety button 109 with respect to trigger 94 as will be more fully explained below.

65 Incident to this turning effort use is made of the key 111 which passes through an opening in the trigger 94 and by engagement with longitudinal slots 112 inside the trigger handle 35 prevents rotation of the trigger within that handle while at the same time permitting axial trigger movement with respect to the handle.

70 Safety button 109 is provided with side slots 150 through which the ends of trigger key 111 project as shown in Figs. 8 and 12. The trigger

spring 110 encircles the trigger rod 94 as shown in Figs. 8 and 13. The two ends of this spring respectively are attached; (a) to an enlarged portion of that rod shown in Figs. 8 and 13 at the sear engaging end thereof; and (b) to the inner end of the safety fixture 109 (again see Fig. 8).

During assembly of the parts shown in Fig. 8 this spring is so wound onto its two end attachments that upon insertion of the trigger key 111 through the safety slots 150 and the trigger, the safety button 109 has exerted thereon a torque tending to rotate it clockwise with respect to the trigger. (In this and later references to rotative direction with respect to the trigger, the directions should be considered as they would appear when viewed from the trigger's outer end—i. e., where it protrudes from handle 35—toward the trigger's opposite or inner end.) This rotative urge positions the safety slots 150 as shown in Figs. 8 and 12 and thereby safeguards the trigger 94 against accidental depression into the gun's handle 35.

Loading and firing

From the foregoing it will be seen that we have provided an improved recoilless firearm which offers important advantages connected with both loading and firing. To place the ammunition round within the weapon it is merely necessary to unlock the breech block 33, withdraw it from the chamber 31 and swing it downwardly to the position shown by Figs. 3 and 13, thus completely freeing the chamber opening.

The ammunition round (only the cartridge case 40 of which is shown in the drawing) is now inserted into the open chamber and the rear of the barrel's bore. When the projectile (not shown) is thrust home in the barrel, centering support is imparted to the forward end of the cartridge case, case head 63 being similarly centered within chamber 31 due to the head's abutting with the breech cone 54.

The breech block 33 (together with bar 34 and handles 35-36) is now moved upwardly and forwardly into the chamber. In approaching and engaging with the cartridge case head 63 the flared recess 130 in the breech block's front comes into abutment with the head and thereby restrains the case against rearward movement.

Counterclockwise rotation of the breech block by bar 34 and handles 35-36 now locks that block into the chamber with the case head's rim in abutment with the breech cone 54 and the case head proper in abutment with the breech block, the primer 56 in alignment with the firing pin 66 and the entire cartridge case 40 centrally positioned within the surrounding chamber 31.

The hammer 92 now has the "cocked" condition shown by Figs. 8 and 13 and the weapon is accordingly ready for firing. The safety button 109 first has to be rotated to release the trigger, whereupon a backward pressure on handle 35's trigger 94 will release the hammer and firing pin 66 to cause detonation of percussion element 56 and ignition of primer and propellant charges 53 and 55, respectively.

The resultant combustion of propellant 55 discharges the projectile (not shown) in the manner earlier described. After this firing, the fired cartridge case is withdrawn from the chamber as follows. The breech block is first unlocked and then withdrawn rearwardly and downwardly out of register with the chamber and into the position on hinge support 75 which Figs. 3 and 13 show. Extraction of the case now becomes pos-

sible. For facilitating such extraction we supplement our hinge-mounted breech block 33 by an extractor represented at 117 in Fig. 13. This extractor, as Fig. 13 shows, is a right-angled piece of metal which fits into a recess in the forward face of breech block 33 and is there held by a retainer bar 118 (see Fig. 13) fastened over the recess by screws indicated at 119 in Fig. 3. A spring 120 urges the extractor's exposed or hooked end inwardly toward the center of the breech block and at the same time towards the forward face of that block.

Summary

From the foregoing it will thus be seen that we have improved the design and extended the usefulness of non-recoil guns wherein the forces of rearward reaction that result from projectile discharge are neutralized by forwardly acting counterforces simultaneously set up by release of the powder gases through an orifice in the gun's breech; that we have provided improved chamber and breech constructions for such recoilless guns; that we have increased the simplicity, ruggedness and compactness of breech actions and of firing mechanisms for recoilless firearm use; and that we have provided improved means for loading and firing the gun.

Our inventive improvements thus are capable of wide application and hence are not to be restricted to the specific form here shown and described by way of illustration.

We claim:

1. In a firearm, the combination of a chamber, a breech block movable into and out of the rearward portion of said chamber and being secured therein when rotated to a locked position and freed for withdrawal therefrom when rotated to an unlocked position, a support member for said breech block hingedly attached to the rear exterior of said chamber and extending radially into pivotal juncture with the center of said block whereby to permit rotative movement of the block between said locked and unlocked positions plus supported block withdrawal from the chamber, a bar extending across and secured to the rear of said breech block, and an operating member affixed to said bar to facilitate turning of said breech block within said chamber and to aid withdrawal of the block from and reinsertion of the block into the chamber.

2. In a firearm, the combination of a chamber, a breech block movable into and out of the rearward portion of said chamber and being secured therein when rotated to a locked position and freed for withdrawal therefrom when rotated to an unlocked position, a support member for said breech block hingedly attached to the rear exterior of said chamber and extending radially into pivotal juncture with the center of said block whereby to permit rotative movement of the block between said locked and unlocked positions plus supported block withdrawal from the chamber, an operating member affixed to said breech block for transmitting turning plus withdrawing and reinserting movements thereto, a firing pin disposed within said breech block and movable axially thereof between a forward released position and a rear cocked position, a hammer attached to the rear of said firing pin, a spring urging said hammer and firing pin towards said forward released position, means effective upon each rotative movement of said breech block from said locked to said unlocked position for camming said hammer and attached firing pin rearwardly against said spring and into said cocked position,

and trigger plus sear means effective to engage said hammer and latch it in its said cocked position against the force of said spring.

3. In a firearm, the combination of a chamber, a breech block movable into and out of the rearward portion of said chamber and being secured therein when rotated to a locked position and freed for withdrawal therefrom when rotated to an unlocked position, a support member for said breech block hingedly attached to the rear exterior of said chamber and extending radially into pivotal juncture with the center of said block whereby to permit rotative movement of the block between said locked and unlocked positions, an operating member affixed to said breech block for transmitting turning plus withdrawing and reinserting movements thereto, a hammer supported from said breech block and disposed for axial movement with respect thereto between a forward released position and a rear cocked position, a spring urging said hammer towards said forward released position, and cam-

ming means effective to move said hammer rearwardly against said spring and into said cocked position upon each rotative movement of said breech block from said locked to said unlocked position with respect to said hinge-mounted support member.
